VENTILATED DRUM FOR DEHYDRATORS

Filed Jan. 13, 1947

UNITED STATES PATENT OFFICE

2,496,225

VENTILATED DRUM FOR DEHYDRATORS

Wallace L. McGehee, Kansas City, Mo., assignor
to McGehee Company, Kansas City, Mo., a cor-
poration of Missouri

Application January 13, 1947, Serial No. 721,842

1 Claim. (Cl. 34—136)

1
This invention relates to apparatus for dehydrating materials from which it is desired to remove substantially all the moisture as the same passes through a horizontally disposed rotatable drum, through the medium of a blast of hot air passing through the machine. It is well known by those skilled in this art that proper dehydration of such materials is more effectively accomplished if the dehydrators are ventilated and air permitted to impinge upon the material as the same passes therethrough.

It is also well known that the wet material entering the machine to be entrained in a stream of hot air is capable of withstanding a hotter stream of air than is possible after such material has passed further into the interior of the drum. Therefore, it is the primary object of this invention to provide a ventilated drum for dehydrators, having means for directing air to the material at a point in the drum where the material has reached a point of dehydration, where the same is incapable of withstanding extremely hot blasts without burning or otherwise becoming damaged.

The most important object of this invention is to provide a ventilated drum for dehydrators, having one or more air intake openings for placing the drum into communication with the atmosphere and manually shiftable closure means for adjustably limiting the amount of air passing into the drum.

Another object of this invention is to provide a ventilated drum for dehydrators having a rotatable shell formed by an inner and outer wall so spaced as to present a hollow, continuous circumscribing chamber in communication with the interior of the drum and for means for receiving air from the exterior thereof in the form of an adjustable closure.

A further object of this invention is to provide in a ventilated drum for dehydrators having the aforesaid inner and outer walls, means for returning a large percent of heat that escapes throughout the length of the drum to its interior as air is directed from its exterior thereinto.

Additional objects will be made clear or become apparent during the course of the following specification, referring to the accompanying drawing, wherein:

Fig. 1 is a substantially central longitudinal sectional view of a ventilated drum for dehydrators made in accordance with my present invention.

2
Fig. 2 is a sectional view, taken on line II—II of Fig. 1.

Fig. 3 is an enlarged fragmentary cross sectional view, taken on line III—III of Fig. 1.

5 Fig. 4 is a fragmentary detailed cross sectional view, taken on line IV—IV of Fig. 3, and

Fig. 5 is a fragmentary substantially central longitudinal cross-sectional view of a modified form of a ventilated drum for dehydrators.

10 The material handling apparatus chosen for illustration, comprises a substantially cylindrical double wall shell, mounted for rotation with its longitudinal axis disposed horizontally and broadly designated by the numeral 10. This shell comprises an inner and outer wall 12 and 14 respectively, the diameter of wall 12 being less than the diameter of wall 14, to present a hollow chamber or space 16, circumscribing wall 12 throughout the greater portion of its length.

15 20 A number of spacers 18, as illustrated in Fig. 2, disposed between these walls 12 and 14, hold the same in spaced relation. The rotatable drum 10 may take any suitable form and the same has been illustrated as having an intake opening 20 at one end thereof through the medium whereof the substances to be dehydrated are introduced and an outlet port 22 at the opposite end of drum 10. The interior of the shell is divided into a number of sections for

25 lifting and shifting material in the usual manner. The first section designated by the number 24 is divided from the remaining part of drum 10 by a radial inwardly directed flange 26. A plurality of longitudinal radial inwardly directed agitators or lifts 28 are fixed within the shell inwardly from flange 26 to a point spaced from outlet opening 22. A frusto-conical wall 30, extending inwardly and diverging from the outlet port 22, directs heavy particles of material

30 35 toward an outlet opening 32. All of these internal parts of the dehydrators form no part of the present invention and, therefore, it is not necessary to describe the same in more detail. Any suitable means for rotating the drum 10 may be used, such as an annular sprocket (not shown) for receiving force through a chain or the like from a prime mover. Suitable sleeves 34 at each end of the drum 10 suitably supported

40 45 provide means for rotatably supporting the drum 10. A portion of the chamber 16 formed by the walls 12 and 14, near the inlet opening 20, is sealed with an insulating material 36. This material extends throughout the length of the section 24 and serves as a means closing one end

50 55 of the chamber 16.

of the hollow chamber 16. A plurality of openings 38 formed within the inner wall 12 are in direct communication with the chamber 16 at one end thereof and the opposite end has a pair of collars 40 and 42. The outer wall 14 is slightly shorter than the inner wall 12 at this said end and the collar 40, which has a plurality of openings 44 therein is affixed directly to these walls 12 and 14, as is clear in Figs. 3 and 4. This collar 40 is preferably formed by turning the outer wall 14 inwardly to present a circumscribing flange around inner wall 12, the inner annular periphery whereof is welded or otherwise secured to inner wall 12. A closure means for the openings 44 in flange 40 is formed by the circumscribing collar 42, which is L-shaped in transverse cross-section, to present a pair of legs 46 and 48, the former of which slideably encircles the inner wall 12. The leg 48 of collar 42 bears against the flange 40 of outer wall 14 and has a plurality of perforations 50, formed therein.

It is clear from the foregoing that collar 42 may be shifted or moved on the inner wall 12 to move its perforations 50 into and out of registering relation with the openings 44 of the flange 40. Obviously the openings 44 and 50 are equally spaced to make it possible for all of said openings to be in mutual registering relationship if such is desired. By the same token, the extent to which these openings are in register may be varied as conditions require.

Fig. 1 clearly illustrates the manner in which air externally of the drum 10, enters through perforations 50 and 44 and travels along the chamber 16 to pass into the openings 38, whereupon this air impinges upon the material passing through the dehydrator. The location of the openings 38 is of prime importance, since the material entering the inlet opening 20 is ordinarily quite fully saturated with moisture and while the same is within the section 24 of drum 10, a large degree of heat may be directed thereto without damaging effect. However, as the material moves inwardly toward the lifters 28 and particles thereof gradually become dry, the extent of heat which is applied to such particles must be diminished to the end that the same will not burn, because of their dryer nature. The amount of air necessary for entrance to the dehydrator will depend directly upon the extent of the moisture contained in the material upon its initial entrance into drum 10 and, therefore, the adjustability of collar 12 becomes quite important.

It is furthermore notable that as the air passes along chamber 16 for entrance into the openings 38, much of the escaping heat passing radially outwardly through the inner wall 12 and which might otherwise be lost and wasted, will be carried toward the inlet end of the drum 10 and thence into the openings 38 for reuse as a drying agent for the material being dehydrated.

Referring now more specifically to Fig. 5 and the modified form of the invention, a drum 100

is of similar nature to that shown and described with respect to Fig. 1 in that the first compartment 102, adjacent to the inlet opening of the dehydrator is of a double wall nature and constitutes a pair of spaced apart telescoping shells 104 and 106. A space is provided between these shells for receiving insulation 108, similar to the insulation 36 shown in Fig. 1. The remainder of the drum 100, however, is of a single wall nature, which wall 110 has a plurality of openings adjacent the section 102 as at 112. A shiftable collar 114 encircles the shell 110 and is provided with a number of openings 116 spaced equal distances to the spacing of openings 112 in the wall 110, whereby manual sliding movement of the collar 114 moves the openings 116 into and out of register with the openings 112. In this modified form it is readily seen that air may be introduced to the substance passing through the dehydrator in the same manner and at the precise point as in the form illustrated in Fig. 1 and the extent of air varied to suit conditions. This modified form eliminates the additional cost of a secondary outer shell as at 14 in Fig. 1 and fails only to utilize lost heat which escapes through the shell 110.

It is understood that ventilated drums for dehydrators may be made having a large number of structural modifications without departing from the spirit of this invention or scope of appended claim.

Having thus described the invention, what is claimed as new and desired to be secured by Letters Patent is:

35 A ventilated drum for dehydrators of the character described comprising a substantially cylindrical shell mounted for rotation about a horizontal axis, said shell comprising an inner and outer wall, said inner wall having at least one opening intermediate the ends thereof and having a diameter smaller than the diameter of the outer wall to present a hollow chamber between the walls in communication with said opening; means for closing one end of the chamber; a perforated wall forming the opposite end of the chamber and an annular band slidably circumscribing the inner wall of the shell adjacent said end wall, said band having a lateral, perforated flange overlapping said end wall, the perforations of the end wall and of the flanges moving into and out of register as the band is moved on said inner wall of the shell.

WALLACE L. McGEHEE.
